UNITED STATES PATENT OFFICE.

EDWARD WALSH, JR., OF ST. LOUIS, MISSOURI.

GLASS SHINGLE.

SPECIFICATION forming part of Letters Patent No. 377,588, dated February 7, 1888.

Application filed June 8, 1887. Serial No 240,581. (No model.)

To all whom it may concern:

Be it known that I, EDWARD WALSH, Jr., a citizen of the United States, residing at the city of St. Louis, State of Missouri, have made 5 a certain new and useful Improvement in Glass Shingles, of which the following is a full, clear, and exact description.

My invention relates to improvements in glass shingles for roofing or other purposes, 10 and has for its object to secure the shingles to the battens without the use of nails or pins, and at the same time insure a perfect bond.

On the accompanying drawings, Figure 1 is 15 a plan of a series of glass shingles constructed and arranged according to my invention; Fig. 2, a transverse section through two adjacent shingles on line 1 1 in Fig. 1; Fig. 3, a longitudinal section through an upper and lower shingle on line 2 2 in Fig. 1; and Fig. 4 a similar view showing a modification of my invention, like letters of reference denoting like parts in all the figures.

In carrying out my invention each glass shingle *a*, which is preferably of a trapezoidal 25 shape, for the purpose hereinafter described, is formed on one side for its entire length with a lip or flange, *b*, curving upward from the upper surface or back of the shingle *a*, and on the other side with a similar flange, which is turned 30 over outward at its upper portion and thence tangentially downward, so as to form a concave groove or channel, *c*, in the bed of the shingle *a* on that side.

The upper edge or "head" of the shingle *a*, 35 for a suitable width between the flange *b* and groove or channel *c*, is turned downward and forward beneath the shingle *a*, so as to form a broad flat hook or catch, *d*, which is at such a distance from the bed of the shingle *a* that the

hook *d* will pass easily beneath the roof-batten 40 *e*, and the shingle *a* be thereby securely held in place.

In forming the roof or other surface to be covered, the shingles *a*, being, respectively, hooked to the battens *e*, as described, are laid 45 so that the lip or flange *b* of one shingle *a* occupies and is confined by the groove or channel *c* of the succeeding shingle *a*, and the lower edge or "tail" or channel *c* of one shingle *a* laps over the upper edge or head and corresponding portion of the groove or channel *c* 50 or the succeeding shingle *a*, whereby a perfect lock to the shingles is obtained.

For insuring the close fitting of the laps formed by the head and tail, respectively, of 55 two adjacent shingles, the head of each shingle *a* is preferably wider than the tail, while the groove *c* of each shingle *a* is smaller at the head than at the tail, by which means the bed of one shingle *a* at the tail, with a corresponding portion of the groove *c*, will lie closely on the "back" of the succeeding shingle *a* at its head, and on the corresponding portion of its groove *c*, to the extent of the lap.

I claim as my invention—

In a glass shingle, the combination of the hook or catch *d*, formed at the head of shingle *a*, and turned downward and forward beneath the shingle *a*, as described, lip or flange *b*, and groove or channel *c*, substantially as shown, 70 and for the purpose described.

In testimony whereof I affix my signature, in presence of two witnesses, this 4th day of June, 1887.

EDWARD WALSH, JR.

Witnesses:

S. L. SCHRADER,
EDWIN SAUTER.
